ABSTRACT

A comprehensive member combining both the caseband and the glass is made out of one piece of a homogeneous translucent material. The peripheral wall of this member surrounds the watch movement and it is thick enough to be practically opaque and to hide the movement edge. The central portion of this member is, on the contrary, made thin enough to form a screen allowing time reading.

3 Claims, 2 Drawing Figures

PATENTED MAR 6 1973

3,719,038

FIG. 1

FIG. 2

WATCHCASE

BACKGROUND OF THE INVENTION

1. Field of the Invention

My invention relates to watchcases and in particular to watchcases of the type comprising, in lieu of a case-band and a separate glass, a one-piece member.

2. Description of the Prior Art

With the watchcases of this type, which are known in the art, this one-piece member is made of a transparent material, such as plexiglass. To hide the movement either an opaque ring is inserted into the peripheral portion of said member or the inner surface of this peripheral portion is coated with a paint.

There are also watchcases known in the art in which such a member has been obtained by welding a ring and a plate together. In this event both the ring and the plate consist of the same material, but the ring has colored particles in suspension which render it opaque, while the plate remains transparent.

It will thus be observed that all the known watchcases have the common drawback to require some additional piece or operation to hide the movement edge, because in each one of these watchcases the material of the member substituted for both the case-band and the glass is originally transparent.

SUMMARY OF THE INVENTION

It is therefore an object of my invention to avoid this common drawback with the watchcases of the type indicated above.

A more particular object of my invention consists of making the one-piece member substituted for both the case-band and the glass of a homogeneous translucent material, the peripheral portion of this member, which is arranged for receiving a watch movement and surrounding the same, being thick enough to hide the movement, while another portion of said member is thin enough to form a screen permitting reading time.

Further objects of my invention will become apparent in the course of the following description.

BRIEF DESCRIPTION OF THE DRAWING

Two embodiments of the watchcase according to my invention are represented diagrammatically and by way of example in the accompanying drawing.

In the drawing:

FIG. 1 is a cross-sectional view of the first embodiment, and

FIG. 2 is a similar view of the second embodiment.

DESCRIPTION OF THE PREFERRED EMBODIMENTS

The watchcase represented in FIG. 1 comprises a member 1 made of sintered aluminum oxide (Al_2O_3). Member 1 has the general shape of a cup. Its peripheral portion constitutes a thick and heavy opaque wall 1a while the central portion 1b is thin and constitutes a translucent screen.

If desired, the aluminum oxide powder can be mixed with a measured load of additives so as to produce a colored member, the portion 1b of which is still translucent.

Since portion 1b is made integral with the wall 1a, changes of the temperature do not modify the stress of

portion 1b to which wall 1a additionally confers a great mechanical stability. Thus, even if the time indication has to be ensured in the conventional manner, i.e. by means of hands extending outwards to the periphery of the watch, portion 1b may be substantially thinner than the known usual glasses. This is enough to render watch hands visible through portion 1b, especially when these hands are black and the sintered corundum is white without coloring additives.

With a watch having a digital time indication member 1 can be made with one or more thin portions which need not extend over the whole visible surface of the watch. According to the distribution of the time indicators member 1 could be made thinner only at one or several separate places. At such places the outer surface of member 1 could be made concave. The smaller the extent of these thinner portions of member 1 the more their thickness can be reduced and the easier time can be read. Reading the time indications of the watch is, of course, best ensured when they are produced by light sources fed from the watch movement. In this event, the screen portion of member 1 operates in a similar manner as a TV-screen.

The manufacture of member 1 does not raise any problem. Before sintering, the aluminum oxide powder can be given such a shape that the piece obtained after sintering only requires a minimum of final machining operations. For instance, holes 2 and 3 provided for the attachment of a wrist-band and securing the watchcase bottom 8, respectively, can be bored after sintering. A boring (not shown) for the passage of a control stem can similarly be provided across wall 1a after sintering. Recess 4 provided for forming screen 1b, shoulder 5 for the abutment of the movement baseplate, recess 6 for a watertight packing 11 and projections 7 constituting the wrist-band attaching lugs shall, on the contrary, be molded before sintering member 1.

For securing bottom 8 consisting of a metal plate holes 3 are provided in the lower face of wall 1a and tapped bushes 9 are glued in these holes so that bottom 8 can be fixed to member 1 by screws 10. Different securing means could also be provided for the bottom 8 as it will appear obvious to those skilled in the art.

Packing 11 sealing the joint between bottom 8 and member 1 can be previously glued or secured in any appropriate manner to either one of these two pieces.

Member 1 can also be sintered with facets so as to appear like a gem after polishing.

The watch movement (not shown) can be held within the watchcase disclosed in any conventional manner, for instance by spring means bearing on bottom 8 and pressing the movement baseplate against shoulder 5.

The only difference between the second embodiment (FIG. 2) and the first one resides in the attaching means which have been provided for the wrist-band. In the second embodiment the bottom 8a consists of a rectangular plate made integral with four projections 12 at its corners. The end of projections 12 is overlapped so as to form anchoring means for a bar 13 to be inserted in the loop of a wrist-band. With a circular watch the bar in question could also be held by a single overlapped projection of the bottom. This bar would only need have its central section held by the bottom projection.

Further modifications will appear obvious to those skilled in the art within the scope of the appended claims.

I claim:

1. A watchcase comprising, in lieu of a case-band and a separate glass, a one-piece member made of a homogeneous translucent material, said member having a peripheral portion adapted for receiving and surrounding a watch movement and being thick enough to

10

hide the movement, and a portion being thin enough to form a screen permitting reading time.

2. A watchcase as claimed in claim 1, said member being made of sintered corundum.

3. A watchcase as claimed in claim 1, said member having as its thin portion a screen capable of producing time images thereon when light sources are fed from the watch movement.
